Patented July 4, 1922.

James A. Hayes

INVENTOR.

UNITED STATES PATENT OFFICE.

JAMES A. HAYES, OF NEW YORK, N. Y.

DESIGN FOR A DOLL.

61,160.

Specification for Design. Patented July 4, 1922.

Application filed April 1, 1922. Serial No. 1,490. Term of patent 3½ years.

To all whom it may concern:

Be it known that I, JAMES A. HAYES, a citizen of the United States, residing at No. 2183 Broadway, in the city, county, and State of New York, have invented a new, original, and ornamental Design for a Doll, of which the following is a specification, reference being had to the accompanying drawing, forming part thereof.

The figure is a front view of a doll, showing my new design.

I claim

The ornamental design for a doll as shown.

JAMES A. HAYES.
